WHISTLE OPERATING MECHANISM

Filed May 26, 1928

UNITED STATES PATENT OFFICE

HENRY BAXTER, OF SCHENECTADY, NEW YORK

WHISTLE-OPERATING MECHANISM

Application filed May 26, 1928. Serial No. 280,722.

This invention relates to mechanism for operating whistles, more particularly to those used on locomotives, and has for its object to provide a simple and efficient means for effecting and controlling blasts of the whistle, which shall be readily applicable to existing designs of whistles and be operable either by fluid pressure or manually as desired.

5 The improvement claimed is hereinafter fully set forth.

In the accompanying drawing: Figure 1 is a side view, in elevation, of a portion of a locomotive boiler, illustrating an application 15 of the invention; Fig. 2, a vertical longitudinal central section, on an enlarged scale, through the operating mechanism, and; Figs. 3, 4, 5 and 6, vertical transverse sections, on the same scale, on the lines, *a a*, *b b*, *c c*, and 20 *d d*, respectively, of Fig. 2.

In the practice of the invention, referring descriptively to the specific embodiment thereof which is herein exemplified, the operating mechanism is enclosed in a casing or 25 housing, 1, located above the boiler, 9, and between the same and the whistle, 10. The casing, 1, is provided with a bolting flange, 1^a, for attachment to a suitable bracket, 3, secured to the boiler. A pipe inlet, 1^b, for 30 admitting steam from the boiler to blow the whistle, leads into one end of the casing and is controlled by a valve, 2, of the single poppet type. The valve, 2, which is located in a chamber at one end of the casing, having 35 a removable cap, 1^c, closes on a seat, 1^d, in the casing, and is fixed on a hollow stem, 2^a, having formed therein the passages, 2^b, disposed on either side of the central web in which is formed the slot, 1^e, and which extends through a passage, 1^f, in the casing, 40 from the valve seat to a chamber, 1^g, from which a tubular lateral outlet extension, 1^h, leads to the whistle, 10. The periphery of the valve stem, 2^a, adjacent the slot, 1^e, is 45 formed to fit closely in the passage, 1^f, and is preferably provided with water-grooves to prevent leakage. Steam from the boiler is supplied to the inlet, 1^b, through a continuously open pipe, 1ⁱ. A transverse slot, 1^j, formed in the central web, 2^c, of the valve

stem, 2^a, is engaged by a curved face head, 4^a, formed on the lower arm of a double armed operating lever, 4, which is pivoted to lugs, 1^k, on the casing, by a pin, 4^b. The upper arm of the operating lever is connected to a cord, 5, or other suitable means for manually imparting movement to the operating lever, upon its pivot pin, 4^b, leading to a point convenient for actuation of the lever by the engineer.

To provide for the operation of the appliance by fluid pressure, when desired, a piston chamber, 1^l, is formed in the casing, at the end thereof further from the inlet, 1^b, said chamber being closed by a removable head, 1^m. A piston, 6, fixed on a stem, 6^a, is fitted in the piston chamber, 1^l, to which fluid pressure, which may be steam or air, is supplied through a pipe, 6^b, controlled by a valve (not shown) which is located in a position readily accessible by the engineer. The piston stem, 6^a, terminates closely adjacent, that is to say, with a slight degree of clearance, to the adjacent end of the stem, 2^a, of the operating valve, so that, when subjected to fluid pressure, it will move said stem, in direction to unseat the operating valve and admit steam to effect a blast of the whistle. A leakage port, 1ⁿ, is formed in the piston chamber, to permit the escape of any motive fluid that may leak past the packing of the piston.

In the manual operation of the appliance, the inlet, 1^b, of the casing being continuously open to the boiler, steam, at boiler pressure, normally maintains the valve, 2, against its seat, and prevents the passage of steam to the whistle. Further, after said valve has been unseated, the boiler pressure tends to return it to its closed position. Movement, by the engineer, of the operating lever, 4, in direction to unseat the valve, permits the flow of steam, through the passages, 2^b, formed in the hollow stem, 2^a, through the casing, to the whistle, thereby effecting a blast thereof, which is terminated by the release of the operating lever, by the engineer.

The power operation of the appliance is effected by the admission of fluid under pressure, through the pipe, 6^b, to the piston chamber, 1^l, resultant upon the opening, by the

engineer, of the valve controlling said pipe, which valve may be of any suitable known construction, adapted for the admission and exhaust of fluid, and not forming, in and of itself, part of the present invention, it is not herein, in detail, set forth.

It will be seen that the appliance hereinbefore described, provides duplicate means for sounding the whistle, by manual and by power operation, respectively. No valve is required in the whistle itself, so that any form of whistle may be used with this mechanism, by removing its operating valve and its hand operating lever, as these are provided for by the invention. Power operation ordinarily eliminates cumbersome rods, jaws, pins, shafts, etc. which must be maintained against wear and vibration, while this mechanism requires merely a simple rope or cable for emergency use only, in case of failure of the power operating means. It further provides the capacity of ready application of power operation means to existing locomotives, adaptable to any location on the locomotive, and capable of fitting in existing clearances, and is economical in that new whistles will not have to be purchased, and no maintenance of the hand operating rigging will be required.

What is claimed as the invention and desired to be secured by Letters Patent, is:

A mechanism for operating whistles, comprising a casing partitioned into first, second, third, and fourth, axially aligned chambers, the first chamber having a port in a side wall for admitting steam from a boiler and a screw cap closing the outer end thereof whereby the interior of said chamber may be opened without interfering with the steam admitting port, the second chamber having a slot in one of its walls for the passage of a lever, the third chamber having a passageway in its side wall threaded for the attachment of a connection to a whistle, said second chamber being in communication with said first and third chambers, and the fourth chamber having a port for admitting pressure fluid, a wall entirely separating the fourth chamber from the third chamber and a screw plug closing the end of the fourth chamber opposite said wall, a valve in the first chamber separating the first chamber from the second chamber when closed and having a stem fitted in the second chamber separating the second chamber from the third chamber and formed with a passageway adapted to lead steam entering the second chamber from the first chamber through the stem to the third chamber when the valve is open, said stem having a slot for the reception of a lever; a lever pivoted to the casing and having an arm projecting through the slot in the second chamber and into the slot in the valve stem; and a piston in the fourth cham-

ber having a stem projecting into the third chamber through said separating wall and adapted to bear upon an end of the valve stem.
